UNITED STATES PATENT OFFICE.

EUGENE TYMESON, OF YONKERS, NEW YORK, ASSIGNOR TO ALEXANDER SMITH & SONS CARPET COMPANY, A CORPORATION OF NEW YORK.

TUBE-THREADING MACHINE.

1,363,377.

Specification of Letters Patent. Patented Dec. 28, 1920.

Application filed November 26, 1913. Serial No. 803,112.

To all whom it may concern:

Be it known that I, EUGENE TYMESON, a citizen of the United States, residing at Yonkers, county of Westchester, and State 5 of New York, have invented certain new and useful Improvements in Tube-Threading Machines, fully described and represented in the following specification and the accompanying drawings, forming a part of the 10 same.

This invention relates to machines for threading the tuft yarns through the tubes of a loom tube frame such as used in looms for weaving Axminster or similar carpets or 15 rugs, the especial object of the invention being to provide an efficient machine for this purpose, in which the tuft yarns shall be threaded by being pushed through from the spool or larger ends of the tubes, instead of 20 by passing hooks through the outer or smaller ends of the tubes and drawing the tuft yarns through the tubes on the return of the hooks.

The broader features of the invention relate to the general organization of the machine for threading the tuft yarns by pushing them through the tubes, including the means for engaging the tuft yarns at the 25 spool ends of the tubes and pushing them through the tubes, with the tube frame properly supported and the tuft yarns positioned for the engagement of the threading means. The invention includes also means for combining or bushing out the yarn ends after they 30 are threaded through the tubes and before trimming, means for letting-off the yarn on the spool side of the threading means to provide the length required for threading through the tubes, an improved comb for 35 holding the yarn ends separated on the spool and during threading, and various features of construction and combinations of parts, preferably applied in machines embodying the general features of the invention, 40 but which may be used also in machines employing other methods of threading the tuft yarns through the tubes.

In the accompanying drawings forming 45 a part of this specification, there is shown a 50 tube threading machine of the preferred

form embodying all the features of the invention, and a modified form of let-off device, and this construction will now be described in detail, and the features forming the invention then specifically pointed out 55 in the claims.

In the drawings:

Figure 1 is a side elevation of the machine, with the frame broken away to show the clamp release rod;

60

Fig. 2 is a front elevation of the machine, with the yarn ends broken away to show the parts;

65

Fig. 3 is a vertical section inside the frame and looking to the left in Fig. 2;

Fig. 4 is a horizontal section on the line 4-4 of Fig. 2;

65

Fig. 5 is a detail sectional elevation of a portion of the clutch trip;

Fig. 6 is a horizontal section on the line 70 6-6 of Fig. 5;

70

Figs. 7, 8, 9 and 10 are detail vertical sections showing successive positions of the parts in threading the tubes;

Figs. 11 to 14 are views illustrating the 75 sidewise movement of the needles for engaging the yarns in threading, Figs. 11 and 12 being front elevations showing successive positions of the needles, and Figs. 13 and 14 plan views with the needles in section and 80 corresponding, respectively, to Figs. 11 and 12 in positions of parts;

80

Fig. 15 is a vertical section looking in the same direction as Fig. 3, and showing a different form of let-off device;

85

Fig. 16 is a plan view of Fig. 15; and

Fig. 17 is a detail section on the line 17-17 of Fig. 15;

Referring now especially to the construction shown in Figs. 1 to 14, A is the frame of 90 the machine, shown as an open frame formed of vertical end standards and horizontal tie-bars, and B the needle frame mounted to slide vertically in frame A. This needle frame B consists of vertical end bars 11 sliding in guides 10 on the front standards A and horizontal top tie-bar 12, in which bar 12 is mounted to slide horizontally a bar 13 carrying the needles a, this needle bar 13 being shown as dovetailed in 95 100

the lower side of bar 12, and spring pressed to the left in Fig. 2 by spring 14 connected to bars 12, 13. The needle frame B is moved vertically by levers 16 mounted in the rear standards A and connected to the needle frame by links 17, these levers 16 being reciprocated vertically through links 18 and cam levers 19 by cams 20 on cam shaft 21. The needle bar 13 is moved sidewise in the 5 needle frame B by side bar 22 sliding in guides 23 in frame B and connected by link 24 to arm 25 on rock shaft 26, which is rocked through cam arm 27 by cam 28 on the end of cam shaft 21 to move needle bar 13 to the right against the tension of spring 14. The frame B thus moves down and up 10 with the needle bar 13 and needles *a* to thread the tubes and return the needles, and the needle bar 13 and needles *a* move sidewise in the frame B to engage the yarns on 15 the downward movement of the needles. The sidewise movement of the needle bar 13 and needles is controlled and their proper position assured by adjustable stops 29 at 20 opposite sides of the frame. The needles *a* preferably are guided throughout their movement by a yielding needle guide *b*, spring pressed downward by spring 30, and carried by rods 31 passing freely through 25 bars 12, 13, and free to move sidewise with needle bar 13 and needles *a* in slots 32 in bar 12, the downward movement of guide *b* being limited by stops 33. The needles *a* in 30 the preferred form shown, are thin plates 35 arranged flatwise to each other across the machine, and passing through guide openings or slots in guide bar *b*, these needles, as shown clearly in Figs. 3 and 7 to 10, being formed with a head slotted vertically to 40 form a fork with long and short prongs 1, 2, so that the needle prongs 1 may pass between the yarns and then by relative sidewise movement of the needles and yarns, the 45 needles be engaged between the prongs 1, 2, as the needles continue their downward movement.

Below the needles *a* is the support for the tube frame *c*, shown as of the common form having the usual tubes *d*, the support consisting of a bar 34 on which the tube frame *c* sits, with the tubes lying on the front of the bar, and a rocking clamp bar 35 in front of the tubes which is pivoted to rock rearward against the front sides of the tubes to 50 clamp them in place and rock forward away from the tubes for insertion and removal of the tube frame, this tube clamp 35 being shown as operated by handle 36. Pivoted on the top of tube clamp 35 is a plate 55 forming a yarn clamp 37 which is pressed rearward by springs 38 to clamp the yarns and pressed forward against the springs out of clamping position and out of the path of the needles *a* by rod 39 sliding in a guide

on bar 34 and operated by cam arm 40 on rock shaft 41 and cam 42. The tube clamp 35 carries also the comb *e* by which the free ends of the yarn are held separated and in proper position for threading, this comb *e* being set into grooves in supports on the top 65 of the tube clamp and spring pressed endwise to hold it in position by a suitable spring pressed slide 3 at one end.

The means for holding the free ends of the 70 yarn may be varied, but the comb shown is preferably used and embodies certain novel features which form a part of the present invention. The comb has inclined yarn-holding slots 4 and shoulders 5 forming 75 hooks overhanging the inclined slots so that the yarn ends may not be drawn from the comb directly upward in the slot direction, but must be moved sidewise to release them from the hooks 5, the upper surface of the teeth being preferably inclined, as shown, 80 so as to guide the yarn ends into the slots 4 in threading the comb. The comb is preferably formed of a piece of sheet metal bent into a loop to form the base of the teeth, but this base may be formed in any other suitable manner. It will be understood that this comb is placed upon the yarns in beaming by passing the comb over the yarns or moving the yarns sidewise into the comb, and then the comb is tied to the spool and 85 acts to hold the yarn ends separate and in proper position before and during threading.

The yarn spools *f*, carrying the yarns *x* 90 may be and are shown as of the common construction. In the tube threader, these spools are carried by clamping heads 44, one of which is spring pressed so as to yield for the insertion and withdrawal of the 95 spool, and these clamping heads 44 are carried by studs 45, free to be rotated with the spool by finger piece 46 on one of the studs, the spool being held against unwinding rotation by ratchet 47 on one of the clamping heads and pivoted pawl 48, which may be 100 released by hand. The clamping heads 44 in the construction now being described, are mounted in arms 49 on rock shaft 50 so as to swing toward and from the path of the needles *a*, this rock shaft 50 being actuated 105 by arm 51 connected by link 52 to cam lever 53 operated by cam 54 against lever return spring 55, to move the spool forward from the position shown in full lines in Fig. 3 to that shown in dotted lines, the spool preferably being returned by hand at the proper time and held in normal position by spring catch 56 taking over pin 57 on one of the arms 49, this catch 56 yielding against the operating pressure when the arms are swung 115 forward by cam 54.

Below the tube support and tubes are mounted the cutting devices for trimming

off the yarn ends after threading through the tubes, and combing or brushing devices for straightening out the yarn ends, these combing or brushing devices preferably acting also to hold the yarn ends during the withdrawal of the needles *a* and thus avoid all danger of the yarn ends being withdrawn with the needles.

Two knives *h*, *i* are shown for trimming 10 off the yarn ends, knife *h* being carried by lever knife bar 58 mounted in arms 59 on rock shaft 60 actuated by arm 61 connected by link 62 to cam lever 63 operated by cam 64 against lever returning spring 65. The 15 other knife, *i*, is shown as carried by knife head 66 sliding in guides on the frame and connected by link 67 to cam lever 68 operated against returning springs 69 by cams 70. The rock shaft 60, carrying knife head 58, 20 is preferably carried on adjustable slide bars 71 on frame bars A, and the guides for knife *i* made adjustable, so that the proper position and action of the knives may be secured.

25 The devices for combing or brushing out the yarn ends and holding them during the withdrawal of the needles, are preferably in the form of brushes, and in the construction shown, brushes *k* are arranged on opposite sides of the needle path and carried by brush heads 72 in arms 73 swinging on shaft 74, and this shaft 74 is mounted to rise and fall so as to move the brushes upward and downward between the positions shown in 30 full and dotted lines in Fig. 9, thus combing or brushing out the yarn ends. The shaft 74 is carried in arms 75 on rock shaft 76, which is rocked by cam arm 77 and cam 35 78 to raise the shaft 74 and brushes against the tension of spring 79, which spring lowers the shaft on release by the cam. The arms 73, carrying the brushes *k*, are rocked in opposite directions to move the brushes together and separate them in proper time, 40 as follows: The front brush arms 73 are connected by link 80 to cam lever 81 operated by cam 82 and returned by a spring (not shown). The rear brush arms 73 are operated by similar means, consisting of link 45 84, cam lever 85, cam 86, and a spring (not shown).

50 Any suitable driving and controlling devices may be used. As shown, the cam shaft 21 is driven through gear 88, pinion 89 and gear 90 from pinion 91 on driving shaft S, and this driving shaft S is driven by a friction clutch consisting of clutch member 92 on shaft S and driving pulley 93 splined on the shaft. Pulley 93 is thrown in and out 55 for clutching and releasing shaft S by clutch lever 94, and a brake 95 is preferably used to stop the machine promptly when shaft S is unclutched from the power, this brake shoe 95 being held against member 92 by ad-

justable stud 96 on clutch lever 94 when 60 the lever is thrown into unclutching position. The clutch lever 94 is moved by hand for operating the machine, and is automatically thrown into position to stop the machine at the end of one rotation of the driving shaft. For this purpose the clutch lever 94 is connected by link 97 to arm 98 on rock shaft 99, spring pressed to unclutch the shaft S by spring 100, and rocked to clutch shaft S to pulley 93 by hand lever 101 on 70 rock shaft 99. Hand lever 101 moves in slotted segment 102, this segment having a shoulder 103 inside which the handle is thrown at the end of the shaft clutching movement, and by which it is held against 80 return until forced off the shoulder by a trip 104 carried by trip lever 105 operated in one direction by trip bar 106 and returned by spring 107 and having a locking pin 108 entering an L-shaped slot 109 in trip bar 85 106. Trip bar 106 is connected at its lower end to lever 110 pivoted in the front standard A with its inner end taking over a pin 6 on one of the side bars 11 of the needle frame B, so that the lever is rocked vertically by the rising needle frame B and returned by spring 7 on the descent of the needle frame. Trip bar 106 is spring 90 pressed to hold pin 108 in the horizontal locking portion of slot 109 by spring 111, 95 and trip bar 106 is moved against the tension of this spring to release pin 108 by cam trip 112 carried by hand lever 101, as the lever returns to normal position.

The operation of this clutch mechanism 100 is as follows:

To start the machine for a tube tread- 105 ing operation, the hand lever 101 is swung inward and held by shoulder 103 to clutch shaft S to driving pulley 93 and release brake 95, and the needle frame is then moved downward. As pin 6 releases lever 110 on this needle movement, rod 106 moves upward and spring 111 moves the upper end of the rod into position with pin 108 in the 110 horizontal part of slot 109, as shown in Fig. 5. When the tubes have been threaded and the needles return to their upper position, shown in Fig. 3, and the machine is to be stopped, the rocking of lever 110 115 by pin 6 on bar 11 draws down rod 106 and rocks lever 105 and trip 104, so as to throw hand lever 101 off shoulder 103, and the lever 101 and shaft 99 are then returned to normal position by spring 100 and through 120 link 97 and lever 94 unclutch pulley 93 from clutch member 92, and raise brake-shoe 95 into contact with clutch member 92, so as to unclutch shaft S and brake it so as to assure the prompt stopping of the shaft. As lever 125 101 moves outward, cam 112 carried thereby, throws link 106 inward so as to move pin 108 into the vertical portion of slot 109,

when spring 107 returns lever 105 and trip 104 to normal position.

A safety device is preferably provided to prevent the descent of the needle bar B, except at the proper time, and thus avoid all danger of injury to the operator in inserting and removing spools. The safety device shown consists of a stop 113 pivoted at 114 and having an arm 115 spring pressed by spring 116 to throw the stop into position beneath bar 12 and rocked to withdraw stop 113 by slotted bar 117 having a slot receiving a pin on arm 115, the slot being formed with a shoulder normally engaging the pin 15 so as to rock shaft 114 and withdraw stop 113 when lever 101 is thrown inward to clutch the driving shaft S for an operation of the machine. The bar 117 has a rounded upper end in the line of trip pin 118 on bar 20 12, so that bar 117 is rocked by this pin 118 when bar 12 passes it, to release the pin on arm 115 from the shoulder on bar 117 and thus permit spring 116 to throw stop 113 inward, thus assuring stop 113 being 25 in position to stop bar 12 and prevent another movement of the needle frame, even though lever 101 should not be tripped to unclutch shaft S. Stop 113 yields against spring 116 to permit bar 12 to pass on its 30 upward movement.

The general operation of the machine is as follows:

The machine is shown in the main views, Figs. 1 to 4, with the parts in the position 35 they occupy when the machine is ready for starting the tube threading operation, the tube frame c and its tubes d and yarn spool f being in position for threading, with the yarn ends x lying over the tops of the tubes 40 and held separated by comb e.

Shaft S is now clutched to pulley 93, as above described, and needle frame B with needle bar 13 and needles a is then moved downward by closed cams 20, acting through 45 levers 19, links 18 and levers 16, until the long prongs 1 of the needle forks are passed between the yarn ends x, the needles during this movement being out of line sideways with their respective tubes d, as shown 50 in Figs. 2 and 11. Needle bar 13 with its needles a then stops its downward movement and is moved sideways by cam 28 acting through cam lever 27, rock shaft 26, lever 25, link 24, and side bar 22, and the 55 needles a are thus moved sideways along the comb e, so as to bend the yarns around the needle prongs 1, and into position to be engaged in the forks between prongs 1 and 2, as the needles descend further. This sideways movement of the needle bar 13 and needles a, also, brings the needles a into position to register with their respective tubes d below them. The relative positions of the parts before and after sideways move-

ment of the needles is shown clearly in Figs. 65 1, 7, and 11 to 14, Figs. 1, 7, 11 and 13 showing the position of parts before this sidewise movement, and Figs. 12 and 14 after this sidewise movement.

The downward movement of the needles 70 is now resumed with the short prongs 2 passing in front of the bent yarns, so as to engage the latter in the forks and move the yarns through the tubes, withdrawing the 75 yarn ends from the comb e. For this movement of the needles into the tubes, the yarn clamp 37 has been thrown forward from the position shown in Figs. 1 to 4 into that shown in Figs. 7 to 10, by rod 39 actuated by lever 40 and cam 42, so as to leave the 80 tubes uncovered for threading. As the needles move downward with the yarns x, also, the arms 49 are swung forward to move the spool f from the position shown in full lines 85 in Fig. 3 to that shown in dotted lines, thus giving sufficient slack for threading without tension on the yarns other than that of drawing the yarn ends from the comb e. Spool f and arms 49 are thus moved by rock 90 shaft 50, arm 51, link 52, lever 53 and spring 55 with the movement controlled by cam 54 against which the lever bears during this movement, the spring catch 56 yielding to permit this movement. The needle guide 95 b moves downward with the needles to guide stops 33 and then spring 30 yields to allow the needles to pass onward through the stationary guide. Fig. 8 shows the position of parts with the threading movement 100 of the needles a completed.

The brushes k are now raised by arm 75, rock shaft 76, arm 77, and cam 78 against spring 79 from the position shown in Fig. 3 until they lie on opposite sides of the yarn ends, and then the brushes are closed together upon the yarn ends and needles by rocking arm 73 on shaft 74 by their respective links 80, 84, levers 81, 85, and cams 82, 86, so as to hold the brushes in the position shown in full lines in Fig. 9, and the brushes 110 are then moved downward by spring 79 into the position shown in dotted lines in Fig. 9, thus combing or brushing out the yarn ends, and the brushes are then separated again to the position shown in Fig. 3 by rocking 115 arms 73. The needles a preferably are moved upward out of the tubes while the brushes k are holding the yarns, as shown in Fig. 9, so that these brushes aid in preventing any tendency to the withdrawal of any 120 of the yarn ends with the needles a.

The yarn ends having thus been combed or brushed out and the needles withdrawn from the tubes, the yarn ends are trimmed off to an even length, this being done by 125 moving the knives h, i together by rocking knife arms 59 and moving knife slide 66 by their respective cams and connections, pre-

viously described, so that the yarn ends are trimmed, as shown in Fig. 10, and the knives then immediately restored to their normal position, as shown in Fig. 3.

- 5 When the needles have been withdrawn from the tubes *d*, the clamp 37, which during the threading operation has been held in the position shown in Figs. 7 to 10, by rod 39 forced forward by cam 42 acting through 10 cam lever 40, is released by cam 42 and clamp 37 is then closed by springs 38 upon the yarn ends lying over the bar of spool frame *c*, as shown in dotted lines in Figs. 1 and 10, and in full lines in Figs. 2 to 4, so 15 as to clamp the yarn ends upon the frame bar and hold them in position relatively to the tubes. Spool *f* is then rotated by hand so as to wind up the slack of the yarn between clamp 37 and the spool, and bar 35 20 with clamp 37 is then rocked forward by handle 36 so as to release the tube frame and yarn ends, and the spool frame and spool *f* are then removed from the machine and clamped together as usual to hold the tube frame on the spool until required for use in 25 the loom.

A new spool *f* with its attached comb *e* is now inserted between the heads 44 and another tube frame *c* is placed in position 30 on the support 34, and the tube clamp 35 and yarn clamp 37 are swung back into tube clamping position, and the comb *e* and yarn ends are put in place on clamp 35. As the spool is inserted between the heads 44, the 35 arms 49 with the spool supports and spool are swung backward by hand from the position shown in dotted lines in Fig. 3 to the position shown in full lines in that figure, the pawl 48 being raised by hand during 40 this operation to permit the spool to turn for letting off yarn, and when the spool frame has reached its rearward position the pin 57 is engaged by spring catch 56 to hold the spool frame and spool in the position 45 shown in full lines in Fig. 3 until the next threading operation of the machine, as previously described. When the spool has been swung back and the comb *e* put in place and as the slack is taken up, the pawl 48 is 50 dropped to hold the spool against rotation. All the parts are now in the position shown in Fig. 3, and ready for another threading operation.

The construction and operation of the machine as shown in Figs. 15 to 17 is the same as that above described, except that these figures show a modified let-off device for avoiding tension on the yarns during threading. In this construction 125 is a bar 55 extending across the machine above the yarns and carried by arms 126 on rock shaft 127, controlled through arm 128 by cam 129 and by crank arm 130, link 131, treadle 132, and spring 133. Bar 125 is held in its

lowered position, shown in dotted lines in 65 Fig. 15, by locking pin 134 entering a hole 135 in a lug on one of the arms 126, this pin being mounted to slide and moved in opposite directions by rocking lever 136 spring 70 pressed by spring 137, and rocked against the spring to release the pin 134 by trip arm 138 on one of the needle bar arms 16.

The operation of this let-off is as follows:

When the spool *f* with its comb *e* has been placed in position for threading, the spool 75 supports being fixed in this construction, bar 125 is lowered by treadle 132 acting through link 131, arm 130, shaft 127 and arms 126, from the full line to the dotted line position shown in Fig. 15, and the bar 80 is held in its lowest position by catch 134 entering hole 135. For this operation, the yarn ends *a* have been left slack so that no tension is put upon the yarn ends by the descending bar. The spool *f* is then rotated so 85 as to draw up the yarn ends into the position shown in Fig. 15, and the spool is then held by pawl 48. When the needle frame and its operating arms 16 descend for threading, trip arm 138 on one of the arms 16 engages 90 lever 136, as shown in dotted lines in Fig. 17, and rocks it against spring 137 to withdraw pin 134 from hole 135 and release arm 126 and bar 125, and spring 133 then returns the bar 125 from the dotted line to 95 full line position in Fig. 15, the smooth movement of the bar as required by the threading movement, being secured by cam 129 acting on cam arm 128, this operation, also, restoring treadle 132 to normal position. 100 The tube threading operation is then the same as above described, the slack on the yarn ends *a* for threading being provided by the release of the yarn loop by bar 125 instead of by swinging the spool *f* forward, 105 as shown in Fig. 3.

It will be understood that many modifications may be made in the form, arrangement and movement of parts shown while retaining the invention defined by the claims, and 110 that the machine illustrated is only a preferred embodiment of the invention. The needles for pushing the yarns through the tubes may be used, also, with other means for engaging the needles with the yarns. 115 Thus, the relative sidewise movement of the yarn and needles for bending the yarn about the long prongs of the needles, may be secured by moving the comb as in present machines. The needles, also, may be moved 120 sidewise, as shown, without moving the tubes, or the tube frame may move sidewise with the needles, in which case the long prongs of the needles may enter the tubes before the sidewise movement. The yarn 125 may be let off during threading by rotating the spool or releasing it so as to permit the threading movement of the needles to draw

off the yarn, or the required length of yarn may be provided by using longer ends on the comb side of the tubes, but the constructions shown are preferred as shortening the comb ends and avoiding the pull necessary for rotating the spool to draw off the yarn.

What is claimed is:—

1. In a tube threading machine, a tube frame support and means for holding the 10 yarn ends in position to be threaded, in combination with means for pushing the yarns through the tubes simultaneously.
2. In a tube threading machine, a tube frame support and means for holding the 15 yarn ends in position to be threaded, in combination with needles arranged at the spool or large ends of the tubes and acting simultaneously to thread the yarns through the tubes from their spool or large ends 20 simultaneously.
3. In a tube threading machine, a tube frame support and means for holding the yarn ends in position to be threaded, in combination with needles moving simultaneously 25 transversely to the yarns and engaging the yarns to loop them over the ends of the needles and then push them through the tubes simultaneously.
4. In a tube threading machine, a tube 30 frame support and means for holding the yarn ends in position to be threaded, in combination with needles moving simultaneously transversely to the yarns to loop them over the ends of the needles and then push them 35 through the tubes simultaneously, and means for producing relative bodily sidewise movement of the yarns and needles for engaging the yarns with the needles.
5. In a tube threading machine, a tube 40 frame support and means for holding the yarn ends in position to be threaded, in combination with needles moving transversely to the yarns to loop them over the ends of the needles and then push them through the 45 tubes, and means for moving the needles sidewise with the yarns for engaging the yarns with the needles.
6. In a tube threading machine, a tube 50 frame support and means for holding the yarn ends in position to be threaded, in combination with needles *a* having forked heads with long and short prongs moving simultaneously transversely to the yarns to loop them over the ends of the needles and then 55 push them through the tubes simultaneously, and means for producing relative bodily sidewise movement of the yarns and needles after the long prongs have passed between the yarns for engaging the yarns with the 60 needles.
7. In a tube threading machine, a tube frame support and means for holding the 65 yarn ends in position to be threaded, in combination with means for pushing the yarns through the tubes simultaneously, and means

moving longitudinally of the yarn for combing or brushing out the ends of the yarn after threading and acting to hold the yarn ends during the withdrawal of the threading means from the tubes.

70

8. In a tube threading machine, a tube frame support and means for holding the yarn ends in position to be threaded, in combination with means for pushing the yarns through the tubes, brushes arranged on opposite sides of the threaded yarn ends, and means for moving said brushes together upon the yarn ends and then longitudinally of the yarn for brushing out the ends of the yarn after threading.

75

9. In a tube threading machine, a tube frame support and means for holding the yarn ends in position to be threaded, in combination with means for pushing the yarns through the tubes, brushes arranged on opposite sides of the threaded yarn ends, and means for moving said brushes together upon the yarn ends before withdrawal of the threading means, whereby the yarn ends are held from withdrawal with the threading means.

80

10. In a tube threading machine, a tube frame support and means for holding the yarn ends in position to be threaded, in combination with needles moving simultaneously 95 transversely to the yarns and engaging the yarns to loop them over the ends of the needles and then push them through the tubes simultaneously, and means moving longitudinally of the yarn ends for combing or 100 brushing out the yarn after threading and acting to hold the yarn ends during the withdrawal of the needles from the tubes.

90

11. In a tube threading machine, a tube frame support and means for holding the 105 yarn ends in position to be threaded, in combination with needles arranged at the spool or large ends of the tubes and acting to thread the yarn through the tubes from the spool or large ends, brushes arranged on 110 opposite sides of the yarn ends at the smaller ends of the tubes, and means for moving said brushes together upon the yarn ends before withdrawal of the threading means and then moving them longitudinally of the 115 yarn ends, whereby the yarn ends are held from withdrawal with the threading means and drawn out.

105

12. In a tube threading machine, a tube frame support and means for holding the 120 yarn ends in position to be threaded, in combination with means for pushing the yarns through the tubes, means for combing or brushing out the ends of the yarn after threading, and means for trimming off the 125 yarn ends after they are combed or brushed out.

110

13. In a tube threading machine, a tube frame support and means for holding the 130 yarn ends in position to be threaded, in

115

120

125

130

combination with means for pushing the yarns through the tubes, brushes arranged on opposite sides of the threaded yarn ends, means for moving said brushes together 5 upon the yarn ends and then moving them longitudinally of the yarn to comb or brush out the ends of the yarn, and trimming devices acting on the yarn ends between the brushes and the tubes after the brushes are 10 moved longitudinally and separated.

14. In a tube threading machine, a tube frame support and means for holding the yarn ends in position to be threaded, in combination with tube threading means, and 15 means moving longitudinally of the tubes for combing or brushing out the ends of the yarn after threading.

15. In a tube threading machine, a tube frame support and means for holding the 20 yarn ends in position to be threaded, in combination with tube threading means, and means moving longitudinally of and parallel with the tubes for combing or brushing out the ends of the yarn after threading and 25 acting to hold the yarn ends during the withdrawal of the threading means from the tubes.

16. In a tube threading machine, a tube frame support and means for holding the 30 yarn ends in position to be threaded, in combination with tube threading means, brushes arranged on opposite sides of the threaded yarn ends, and means for moving said brushes together upon the yarn ends and 35 then longitudinally of the yarn for brushing out the ends of the yarn after threading.

17. In a tube threading machine, a tube frame support and means for holding the 40 yarn ends in position to be threaded, in combination with tube threading means, means for combing or brushing out the ends of the yarn after threading, and means for trimming off the yarn ends after they are combed 45 or brushed out.

18. In a tube threading machine, a series 50 of needles α having forked heads formed with long and short prongs 1, 2, in combination with means for advancing the needles in a straight line to move the long prongs between the yarns and means for then producing relative bodily sidewise movement of the needles and yarn to bend the yarn around the long prongs and engage 55 the yarn in the needle forks on the further movement of the needles in the same direction as said straight line movement.

19. In a tube threading machine, a series 60 of needles α having forked heads formed with long and short prongs 1, 2, in combination with means for advancing the needles to move the long prongs between the yarns, and means for then moving the needles sidewise to bend the yarn around the

long prongs and engage the yarn in the needle forks on the further movement of the needles.

20. In a tube threading machine, the combination with spool supporting and tube 70 threading means, of a comb for holding the yarn ends separated for the action of the threading mechanism, having its yarn slots inclined and the comb teeth formed with shoulders overhanging the inclined slots, 75

21. In a tube threading machine, the combination with spool supporting and tube threading means, of a comb for holding the yarn ends separated for the action of the threading mechanism, having its yarn slots 80 inclined and its comb teeth formed with shoulders overhanging the inclined slots, and the tops of the teeth inclined to guide the yarns beneath the shoulders into the inclined slots. 85

22. A comb for holding the free ends of tuft yarns in carpet manufacture, consisting of a bar adapted to be detachably secured to the spool, and having teeth constructed to form inclined yarn slots 4 and 90 shoulders 5 overhanging the outer ends of the slots. 95

23. A comb for holding the free ends of tuft yarns in carpet manufacture, consisting of a bar adapted to be detachably secured to the spool, and having teeth constructed to form inclined yarn slots 4 and 95 shoulders 5 overhanging the outer ends of the slots, the outer ends of the teeth being inclined to form tapering guides directing 100 the yarn into the slots in placing the comb on the yarn.

24. In a tube threading machine, in combination with a spool support and tube 105 threading mechanism, means for moving the spool support toward the tubes during threading to provide slack for passing the yarn ends through the tubes.

25. In a tube threading machine, in combination with a spool support and tube 110 threading mechanism, means for moving the spool support toward the tubes during threading to provide slack for passing the yarn ends through the tubes, and means for returning the spool support to normal position after the completion of the threading operation and stoppage of the machine. 115

26. In a tube threading machine, the combination with a tube support and tube threading devices, spring pressed clamp 37 120 for holding the yarn ends clamped after threading, and means for moving said clamp out of the path of the tube threading devices for threading and releasing it for clamping the yarns. 125

27. In a tube threading machine, the combination with tube threading devices and operating mechanism therefor, of manually controlled means for starting said mechanism, and a stop in the path of the tube 130

threading device removed by the manual operation of the starting means.

28. In a tube threading machine, the combination with tube threading devices and operating mechanism therefor, of manually controlled means for starting said mechanism, means for stopping the machine at the end of each threading operation, a stop in the path of the tube threading devices 10 moved by the manual operation of the starting means, and means for returning said stop into the path of the threading devices independently of the stoppage of the machine, whereby the operation of the tube 15 threading devices is prevented independently of the machine operation.

29. In a machine of the kind described, means for holding a loom tube frame in position to be threaded, and threading mechanism, including devices arranged to double the yarns back on themselves over the ends of the same, and means for then moving said devices and yarns simultaneously through all the tubes from the rear or spool 25 end of the tubes.

30. In a machine of the kind described, means for holding a loom tube frame in vertical position to be threaded, means for pushing the yarns downward through the tubes of said frame from the rear or spool 30 ends of the tubes toward the opposite ends of the tubes, and means for engaging the yarn ends beyond said opposite tube ends and stripping them into holding position by 35 movement parallel with the yarn while the pushers are retracted.

31. In a machine of the kind described, yarn drawing mechanism arranged to push a complement of yarns simultaneously 40 through the tubes of each tube frame from the rear or spool end of the tube toward the opposite end as successive tube frames are put in position, including means for each tube carrying at its forward end the yarn 45 as said end moves forward to enter the tube at said rear or spool end of the tube, and means to comb and clamp the free ends of the yarns by movement parallel with the yarn while the pushing mechanism is being 50 withdrawn from the tubes.

32. In a machine of the kind described, means for holding a loom tube frame in position to be threaded, threading mechanism for placing the yarns in the tubes, and 55 brushing means on opposite sides of the yarn moving longitudinally of the tubes for brushing the free ends of said yarns away from the threading mechanism.

33. In a machine for acting upon tuft 60 yarns in carpet manufacture, the combination with means to hold a series of such yarns, means to support a tube frame in relation to the yarns to be threaded therethrough, a series of pushers with means to 65 cause relative movement between the same

and the tubes first to enter the pushers through the large ends of the tubes and through the tubes and then to position them without the same, said pushers engaging the yarns prior to entering the large ends 70 of the tubes, and means to cause relative bodily lateral movement between the pushers and the yarns to insure better engagement between the same, said yarns being carried into the large end of the tubes simultaneously on the first of said positioning movements.

34. In a machine for acting upon tuft yarns in carpet manufacture, the combination with means to hold a series of said 80 yarns, means to support a tube frame in relation to the yarns to be threaded therethrough, a series of pushers, and means to cause relative lateral bodily movement between the same and the tubes of the tube 85 frame to carry the yarn simultaneously into the large ends of the tubes and through the tubes and to return them to position, said means acting first to position the pushers simultaneously to engage the yarns, then 90 to position the pushers simultaneously through the large ends of the tubes and through the tubes, then to position them without the tubes.

35. In a tube threading machine, a tube 95 frame support, a series of pusher needles, means for holding the yarn ends distended between the needles and the large ends of the tubes, and means to move the needles transversely the yarns to push the latter 100 simultaneously through the large ends of the tubes, the needle movement being interrupted when the needles are brought into position to engage the yarns, and means on the interruption of said needle movement 105 to effect relative lateral bodily movement between the yarns and the needles to wrap the yarns around the needles.

36. In a tube threading machine, a tube 110 frame support, a series of pusher needles, means for holding the yarn ends distended between the needles and the side of the tube frame having large ends, means for moving the needles to thread the yarns simultaneously through the tube frame large ends, 115 said means acting to move the needles simultaneously first to a position with their front ends between the successive yarns, then to interrupt the movement, then to resume the movement to carry the yarns into the large 120 ends of the tubes and through the tubes, then to retract the needles, means to cause relative lateral bodily thread-engaging movement between the needles and the yarns when the needle movement is interrupted to 125 insure better engagement of the yarn by the needles, and means for stripping the yarns from the needles beyond the small ends of the tubes.

37. In a tube threading machine, a tube 130

- frame support, means for holding the tuft yarns in position to be threaded, a series of needles, means for causing relative movement between the needles and the tubes 5 transversely the yarns to thread the latter simultaneously through the tubes, and means for imparting a lateral yarn engaging bodily movement to the needles.
38. In a machine of the kind described, 10 means for holding a loom tube frame in position to be threaded with the tubes vertical and the large ends of the tubes upward, means for holding the yarn ends above the tubes in position to be threaded, a vertically 15 moving needle carrier above the yarn ends and needles mounted in said carrier, and means for actuating the carrier to operate the needles to engage and thread the yarn ends through the tubes on the downward movement of the carrier and withdraw the 20 needles on the upward movement of the carrier.
39. In a machine of the kind described, 25 means for holding a loom tube frame in position to be threaded with the tubes vertical and the large ends of the tubes upward, means for holding the yarn ends above the tubes in position to be threaded, a vertically moving needle carrier above the yarn ends, 30 and needles mounted in said carrier, means for actuating the carrier to operate the needles to engage and thread the yarn ends through the tubes on the downward movement of the carrier and withdraw the needles 35 on the upward movement of the carrier, and means for combing or brushing out the ends of the yarn after threading.
40. In a machine of the kind described, 40 means for holding a loom tube frame in position to be threaded with the tubes vertical
- and the large ends of the tubes upward, means for holding the yarn ends above the tubes in position to be threaded, a vertically moving needle carrier above the yarn ends and needles mounted in said carrier, means 45 for actuating the carrier to operate the needles to engage and thread the yarn ends through the tubes on the downward movement of the carrier and withdraw the needles on the upward movement of the carrier, 50 and means for trimming the yarn ends after they are combed or brushed out.
41. In a machine of the kind described, 55 means for holding a loom tube frame in position to be threaded with the tubes vertical and the large ends of the tubes upward, means for holding the yarn ends above the tubes in position to be threaded, a vertically moving needle carrier above the yarn ends and needles mounted in said carrier, means 60 for actuating the carrier to operate the needles to engage and thread the yarn ends through the tubes on the downward movement of the carrier and withdraw the needles on the upward movement of the carrier, 65 and means for causing a relative bodily side-wise movement between the needles and yarns prior to threading to insure better engagement of the yarns by the needles, and means for stripping the yarns from the needles after they have been threaded through 70 the tubes.

In testimony whereof, I have hereunto set my hand, in the presence of two subscribing witnesses.

EUGENE TYMESON.
